CLAIM

I claim the ornamental design for a slat for venetian blinds.

DESCRIPTION

FIG. 1 is an isometric view looking downwardly at the front of the slat for venetian blinds.

FIG. 2 is an isometric view similar to FIG. 1 with the slat having been rotated through 90 degrees.

FIG. 3 is an isometric view of the rear of the slat.

FIG. 4 is a left side elevation of the slat.

FIG. 5 is a front elevation of the slat.

FIG. 6 is an bottom plan view of the slat;

FIG. 7 is a right side elevation of the slat.

FIG. 8 is a rear view of the slat.

FIG. 9 is a top view of the slat.

FIG. 10 is an isometric view of the slat, shown assembled in a venetian blind in an open position.

FIG. 11 is an isometric view similar to FIG. 10 only in closed position; and,

FIG. 12 is a left-side elevation view shown assembled in a venetian blind in an open but retracted position.

The broken line showing is for illustrative purposes only and forms no part of the claim design.
